UNITED STATES PATENT OFFICE.

GEORGE E. LONG, OF CHATTANOOGA, TENNESSEE.

PACKING CUTTER.

Application filed August 5, 1926. Serial No. 127,389.

This invention relates to devices for cutting packing and particularly to devices for cutting strips of packing into short sections.

The general object of the present invention is to provide a cutting mechanism of this character which is very simple, which is easily manipulated, and by which strips of packing may be cut into sections of any required length for fitting around and packing 10 piston rods, packing glands, for use as gaskets or the like.

A further object is to provide a device of this character by which packing may be readily cut without any calculation and 15 another object is to provide a cutting device of this character which will make either square cuts, that is cuts at right angles to the axis of the packing, or inclined cuts.

My invention is illustrated in the accompanying drawings wherein:—

Figure 1 is a front elevation of a packing cutter constructed in accordance with my invention;

Fig. 2 is a section on the line 2—2 of 25 Figure 1;

Fig. 3 is a vertical sectional view through the guideway looking toward the front of the cutter body;

Fig. 4 is a fragmentary radial section 30 through the guideway of the body and the stop;

Fig. 5 is a face view of a stop for use in cutting lapped packing;

Fig. 6 is a fragmentary face view of the 35 guideway, showing the slot for cutting the abutting ends of packing;

Fig. 7 is a like view to Figure 6 but showing the inclined slot;

Fig. 8 is a fragmentary top plan view 40 of the knife carrier used with the slot shown in Figure 6;

Fig. 9 is a like view but showing the form of carrier used with the slot shown in Figure 7.

Referring to these drawings it will be seen 45 that my mechanism includes a body which is designated generally 10 which is formed with the hollow base 11 having flanges 12 whereby the base may be attached to any suitable support. This body 10 is formed of a hollow casting having openings 13 whereby to make the casting lighter and provided with an annular outwardly projecting portion 14 having at its outer end the annular

flange 15 which extends entirely around the 55 body and at right angles to the longitudinal axis thereof.

The front of the body has a diametrically extending web 16 centrally apertured and screw-threaded for the support of the pilot 60 pin 17. The front face of the flange 15 is formed with the annular groove 18, the walls of which are disposed at an angle 90° to each other and outward of this groove the face of the flange 15 is formed with graduations 19. 65 At its upper end the flange is provided with a slot 20 which, in Figure 6, is shown as extending directly downward toward the center of the cylindrical body but which may be disposed at an angle of 45° to the flange 70 15. This slot 20 extends vertically through the flange and through or into the cylindrical portion 14 of the body. This slot 20 for square cuts is about $\frac{1}{16}$ th of an inch wide whereas for lap cuts, that is where the slot 75 is inclined as in Figure 7, the slot is about $\frac{3}{32}$ nds of an inch wide. The body has a circular opening 21 at its rear end, the rear face of the body being inclined upward and forward and the upper end of the body just 80 above the opening 21 is provided with the barrel 22 constituting a bead.

Pivottally mounted upon the bead 22 is the knife carrier 23. The rear end of this knife carrier is forked and embraces the 85 barrel or bead 22 and is pivotally engaged therewith by means of a transverse pin 24. Forward of this forked portion 25 the knife carrier has a slightly recessed face and disposed in this recessed face is the knife 26 90 having a beveled cutting edge and formed with a central slot 27 through which a set screw or cap screw 28 passes, the screw 28 engaging with the face of the knife carrier thus permitting the knife to be adjusted 95 vertically to a slight extent and then clamped in its adjusted position. The carrier is provided with a handle 29. Where the slot 20 is disposed at right angles to the flange 15, the knife 26 is, of course, disposed in a plane 100 parallel to the handle 29 and at right angles to the pivot pin 24 but where the slot 20 is inclined as in Figure 7, the knife is mounted upon the carrier at an inclination, as shown in Figure 9, where the knife carrying 105 face of the handle is disposed at an inclination to the longitudinal axis of the carrier.

Mounted upon the flange 15 for adjust-

ment around said flange in accordance with the graduations 19 is the stop 30. This is formed with a vertical groove 31 adjacent its outer face into which the flange 15 fits and extending through the front wall of this groove 31 is a set screw 32 having a knurled head so that the stop may be adjusted to any desired position around the flange 15 and held in its adjusted position. Where the stop is to be used with the knife as shown in Figure 8 with the slot 20 at right angles to the pivot pin of the knife carrier, the stop is formed with a flat face at right angles to the plane of flange 15 but where the device is intended to cut lap joints or, in other words, make cuts at an angle of 45°, the face 33 of the stop against which the end of the packing strip bears is disposed at an angle of 45°. (See Figure 5.) While I have referred to the slot 20 in Figure 7 and the knife in Figure 9 and the stop in Figure 5 as being set at an angle of 45°, it is to be understood that any desired angle might be used. While I do not wish to be limited to the particular graduations 19 illustrated, preferably the face of the packing cutter will be divided by graduations into six equal parts and sub-divided into 64ths of an inch and the barrel 14 of the cutter will have a diameter of six inches. Thus, by dividing the cutter face into six equal parts, and setting the stop at the first division to the right of the slot, or $1/6$ th of the diameter of the cutter, a piece of packing can be cut to exactly the size of a one inch valve stem, piston rod, or the like. The sub-division of the face into 64ths will give any desired size or cut of packing. If $1/64$ th of an inch clearance is desired between the ends of the packing on a one inch rod or valve stem, then the stop may be set at $1/64$ th less than one inch or it may be set for $1/32$ nd less or for any clearance desired. The cylindrical or barrel portion 14 and the flange 15 constitute a guideway for the packing and in the use of this device the stop is set at the desired position, the knife raised, and the packing slipped around the barrel 14 until the end of the packing bears against the stop. Then the knife is lowered and cuts off the packing. This cutter will give accurate and identical lengths of packing with parallel ends and the same amount of clearance between the ends of each piece of packing, thus greatly eliminating the blowing and scoring of valve stems and rods. Preferably the graduation on the face of the cutter starts at the left of the knife slot and would be graduated clockwise. While I do not wish to be limited to this, preferably I have provided a pilot pin 17 which extends out approximately 8" from the member 16 and provided an opening 34 so that a spool of packing may be mounted in the manner of a roller upon the pilot pin 17

and the end of the packing carried out through the opening 34 and thus carried around the barrel or cylindrical portion 14.

I claim:—

1. A packing cutter comprising a flanged guideway for the packing and having graduations, a stop adjustable along the guideway in accordance with said graduations, a knife operating across the guideway, and a spindle upon which a roll of packing may be mounted, the guideway having an aperture through which the packing may extend and be pulled out onto the face of the guideway.

2. A packing cutter comprising a cylindrical guideway for the packing, a knife operating across the guideway, the guideway being provided with graduations, and a stop movable along the guideway toward or from the knife, the cutter being hollow and having a central spindle upon which a roll of packing may be mounted, and the guideway having at one point an aperture through which the packing may extend and by which the packing may be pulled out onto the face of the guideway.

3. A packing cutter comprising a hollow body formed to provide a cylindrical guideway having a flange at one end, the body having a supporting base, a web extending diametrically across the body at its flanged end, the opposite end of the body being open, a spindle engaged with the web and projecting longitudinally through the body and through the open end thereof, a knife carrier mounted upon the body for swinging movement, and a knife carried thereby and operating across the guideway, the flange being slotted to receive said knife.

4. A packing cutter comprising a hollow body formed to provide a cylindrical guideway having a flange at one end, the body having a supporting base, a web extending diametrically across the body at its flanged end, the opposite end of the body being open, a spindle engaged with the web and projecting longitudinally through the body and through the open end thereof, a knife carrier mounted upon the body for swinging movement, a knife carried thereby and operating across the guideway, the flange being slotted to receive said knife, and a stop shiftably mounted upon the flange for adjustment toward or away from said knife, the face of the body being graduated.

5. A packing cutter comprising a hollow approximately cylindrical body having a cylindrical guideway at one end and an annular flange extending at right angles to the face of the guideway, the face of said flange being graduated, a web extending diametrically across the flanged end of the body, the opposite end of the body being open, a pilot pin mounted upon the web and extending axially through the body, the

guideway being open at one point to permit the passage of packing from the pilot pin through said opening, a knife carrier pivotally mounted upon the body at its open end, 5 a knife mounted upon the carrier and adapted to operate across the guideway, the flange being slotted for the passage of the knife, a

stop slidably mounted upon the flange and being adjustable around the flange in accordance with said graduations, and means for holding the stop in adjusted positions.

In testimony whereof I hereunto affix my signature.

GEORGE E. LONG.
